(57) CLAIM

We claim the ornamental design for a wireless communications device, as shown and described.

DESCRIPTION

FIG. 1 is a front perspective view of a wireless communications device embodying the design without a clip in order to show aspects of the design that are not otherwise apparent. FIG. 2 is a back perspective view of the wireless communications device shown in FIG. 1.

FIG. 3 is a right side view of the wireless communications device shown in FIG. 1.

FIG. 4 is a front view of the left side of the wireless communications device shown in FIG. 1.

FIG. 5 is a left side view of the wireless communications device shown in FIG. 1.

FIG. 6 is a bottom view of the wireless communications device shown in FIG. 1.

FIG. 7 is a back view of the wireless communications device shown in FIG. 1.

FIG. 8 is a top view of the wireless communications device shown in FIG. 1.

FIG. 9 is a front perspective view of the wireless communications device embodying the design with a clip attached.

FIG. 10 is a back perspective view of the wireless communications device with the clip attached.

FIG. 11 is a right side view of the wireless communications device with the clip attached.

FIG. 12 is a front view of the left side of the wireless communications device with the clip attached.

FIG. 13 is a left side view of the wireless communications device with the clip attached.

FIG. 14 is a back view of the wireless communications device with the clip attached.

FIG. 15 is a bottom view of the wireless communications device with the clip attached; and,

FIG. 16 is a top view of the wireless communications device with the clip attached.
